W. E. WHITE

FORM SUPPORT

Filed Jan. 7, 1922

UNITED STATES PATENT OFFICE.

WILLIAM E. WHITE, OF CHICAGO, ILLINOIS.

FORM SUPPORT.

Application filed January 7, 1922. Serial No. 527,595.

To all whom it may concern:

Be it known that I, WILLIAM E. WHITE, a citizen of the United States, and resident of Chicago, in the county of Cook and State 5 of Illinois, have invented certain new and useful Improvements in a Form Support, of which the following is a specification.

My invention relates to supporting devices for forms and particularly to a novel construction adapted for easy manipulation without the use of special tools.

In the device of my invention I provide hangers which may constitute the depending legs of a stirrup and mount a sleeve or clasp 15 for vertical sliding movement on each of the legs. A bracket adapted to retain a form pan in a desired location is held in interlocked relation to the hanger and sleeve by gravity action of the sleeve. To disengage 20 the bracket and permit the lowering of the form pans it is only necessary to move the sleeve upwardly to the extent of disengaging it from a notch in the bracket, whereupon the bracket is separated by its own 25 weight. A construction such as described is advantageous in that the manner of use is simplified. There are no loose parts which may become separated with the exception of the bracket which constitutes but a small 30 part of the total cost of the assembly.

The invention will be more readily understood by reference to the accompanying drawings, wherein,

Fig. 1 is a sectional view through a molded 35 floor and beam showing the forms held in place by the device of my invention;

Fig. 2 is a side elevation partly in section on the line 2—2 of Fig. 1;

Fig. 3 is an enlarged perspective view of 40 the moving parts of my invention;

Fig. 4 is an enlarged side view with a part 45 of the sleeve broken away, and,

Fig. 5 is a sectional view upon the line 5—5 of Fig. 4.

In the drawings it will be seen that the purpose of my invention is to provide means for supporting form pans 10, of well known construction. These are utilized to mold a floor slab 11, and a beam 12. The bottom of 50 the beam is outlined by a plank 13. This rests upon joists 14, which serve to carry the weight of the molded concrete. Interposed between the plank and the joist is a member in the form of a stirrup having an upper 55 plate 15 and depending legs, one on each side of the joist. These legs are shown as

integrally joined to the plate 15, but as indicated in a co-pending application, Serial No. 524,445, filed Dec. 23, 1921, they may be formed separately and be adapted for dis- 60 engagement.

The legs are shaped to provide an intermediate portion 16, adapted to lie against the joist 14, this portion having a plurality of vertically spaced apart apertures 17. 65 The margins 18 of the legs or hangers are laterally deflected to lie in a plane outside of the plane of the central portion 16 and to constitute guides for a sleeve or clasp 19, the inturned edges 20 of which extend 70 around the flanges 18. This sleeve acts as a lock for a bracket 21, the inner end of which is provided with upper and lower projections 22, 23, respectively, adapted to enter two of the apertures 17 in the hanger. 75 In the upper edge of the brackets near the upper projection 22, I provide a notch 24. The outer end of the bracket may have a lug 25, for an obvious purpose.

The sleeve has an elongated aperture 26 80 therein, of a length slightly greater than the over-all vertical depths of the bracket. The bracket is adapted to be inserted in the aperture in such position that the projections 22, 23, therein occupy two of the recesses in the 85 hanger. Thereupon the sleeve or locking member is permitted to drop by gravity and to engage the notch 24 in the upper edge of the bracket. In this position the bracket is securely held against displacement, the 90 weight sustained by the bracket being held by the combined resistance of the interlock between the sleeve and bracket and the abutment of the lower projection on the bottom of its cooperating recess. 95

To displace the bracket it is only necessary to apply force to the locking member to move the same upwardly, whereupon the bracket will rotate about the lower projection and fall out of its position. 100

Obviously the device is capable of much modification and I do not wish to be limited except as indicated in the appended claims.

I claim:

1. In a form supporting device, the combination of means adapted to rest upon a supporting joist and provided with depending notched legs, a sleeve guided and vertically reciprocable on a leg, and a bracket having a portion adapted to cooperate with 105 said sleeve and with a notch in said leg to interlock the bracket with the leg. 110

2. In a form supporting device, the combination of a stirrup having depending apertured legs, the marginal edges of which are adapted to act as guides, a sleeve vertically slidable thereon, and a bracket adapted to cooperate with the sleeve and provided with a projection adapted to enter an aperture in said leg whereby the bracket is disengageably interlocked with the leg of a stirrup.
3. In a form supporting device, the combination of a stirrup having depending apertured legs, the marginal edges of which are adapted to act as guides, a sleeve vertically slidable thereon, and a bracket adapted to cooperate with the sleeve and provided with a projection adapted to enter an aperture in said leg whereby the bracket is held in interlocked relation to the leg by the gravity action of the sleeve.
4. In a device of the class described, the combination of a support adapted to rest upon a joist and provided with depending recessed legs, a sleeve guided upon each leg and provided with an aperture in alignment with the recesses in said leg, and a bracket adapted to project through the aperture in the sleeve and to engage a recess in said leg and to be held in interlocked relation with the leg by said sleeve.
5. In a device of the class described, the combination of a support adapted to rest upon a joist and provided with depending recessed legs, a sleeve guided upon each leg and provided with an aperture in alignment with the recesses in said leg, a bracket having a projection upon its inner end adapted to co-operate with a recess in said leg and a notch on its upper surface, said bracket being adapted to project into the aperture in the sleeve in such position that the projection therein engages a recess in the leg and the notch in the upper surface thereof cooperates with the sleeve whereby the parts are held in interlocked relation by gravity action of the sleeve.
6. In a form supporting device, the combination of a stirrup having notched depending portions, the marginal edges of the depending portions being laterally deflected to lie in a plane outside of the plane in the central portion thereby forming guides, a sleeve slidable on said guides, said sleeve being provided with an elongated aperture opposite the recesses in said depending portion, and a bracket having a projection adapted to enter a recess in said depending portion, and with a notch adapted to be engaged by the portion of the sleeve at the upper end of said elongated aperture whereby the bracket is held in adjusted position by gravity action of the sleeve and being adapted to be released by upward sliding movement of the sleeve relative to the bracket.
7. In a device of the class described, the combination of a depending leg having notches therein, a clasp slidable on the marginal edges of the leg as a guide, and a bracket having a portion adapted to enter one of the recesses in said leg and being notched on its upper edge for engagement with said clasp, the clasp being held in engagement with the bracket by gravity action.
8. In a form support, the combination of means including a depending leg having vertically spaced recesses, a separable bracket having a pair of vertically spaced projections adapted to engage two of said recesses, and a locking member slidable on said leg and adapted to engage the bracket by gravity near its upper projection and to prevent the separation of the bracket from the leg by rotation about its lower projection.

Signed at Chicago, Ill., this 4th day of January, 1922.

WILLIAM E. WHITE.
